FUSED DROP-OUT CUTOUT

David C. Hubbard and William L. Hollander, Centralia, Mo., assignors to A. B. Chance Company, Centralia, Mo., a corporation of Missouri

Application August 8, 1949, Serial No. 109,146

12 Claims. (Cl. 200—114)

1

The present invention relates to fused drop-out cut-outs, and is particularly concerned with drop-out cut-outs of the type which may utilize any standard universal fuse link now on the market, and which may be opened manually at the top as a disconnect, or opened automatically at the bottom responsive to the rupture of the fuse link.

One of the objects of the invention is the provision of an improved fused cut-out in which the lower contact of the fuse tube is ejected from the bottom contact arm of the support upon rupture of the fuse link, so that the fuse tube will hang with its opening down before and after operation, thus protecting the fiber liner of the fuse tube from all adverse weather conditions.

Another object is the provision of an improved cut-out structure which is especially adapted to delay the actual parting of the lower contacts, due to fuse link rupture, until after the arc has been extinguished within the fuse tube, so that the arc will always be extinguished before the physical parting of the contacts takes place.

Another object of the invention is the provision of an improved cut-out adapted to pull the fuse link from the fuse tube even when the rupturing currents are too light to generate sufficient gases within the fiber liner to eject the link rapidly.

Another object of the invention is the provision of an improved cut-out which is "trip free" in that the automatic mechanism, which controls its opening responsive to the rupturing of a fuse, may operate, even when the lineman is closing the upper contacts of the cut-out, in the event the fault still exists on the line.

Another object is the provision of firm stops to arrest the skyrocketing which is due to jet action, so that the contact springs will not be overstressed and so that the jet action will be employed to assure the retention of the upper trunnions by the upper contact arm as long as the blast exists.

Another object is the provision of an improved mechanism for the lower contact and ejector arm, by means of which the ejector arm is so rotated, responsive to the rupture of a fuse link, that the trunnion is moved out of its supporting groove, so that it can be ejected by the action of another spring carried by the contact supporting arm.

Other objects and advantages of the invention will be apparent from the following description and the accompanying drawings, in which similar characters of reference indicate similar parts throughout the several views.

2

Referring to the drawings, of which there are four sheets:

Fig. 1 is a side elevational view in partial section, showing a fused drop-out cut-out embodying the invention, with the two alternative open positions, shown in dotted lines;

Fig. 2 is a top plan view, taken on the plane of the line 2—2 of Fig. 1;

Fig. 3 is a bottom plan view, taken on the plane of the line 3—3 of Fig. 1, looking in the direction of the arrows;

Fig. 4 is a front elevational view, taken on the plane of the line 4—4 of Fig. 1, looking in the direction of the arrows;

Fig. 5 is a side elevational view of the upper contact arm and connector fixture;

Fig. 6 is a fragmentary sectional view, taken on the plane of the line 6—6 of Fig. 5, looking in the direction of the arrows;

Fig. 7 is a fragmentary sectional view, taken through the mechanism at the bottom of the fused cut-out assembly of Fig. 1, with the parts in the position which they assume when the fuse is ruptured, but before the contact has been ejected from the contact supporting arm;

Fig. 8 is a fragmentary sectional view, taken on the plane of the line 8—8 of Fig. 7, looking in the direction of the arrows;

Fig. 9 is a sectional view, taken on the plane of the line 9—9 of Fig. 7, looking in the direction of the arrows;

Fig. 10 is a sectional view, taken on the plane of the line 10—10 of Fig. 9, looking in the direction of the arrows;

Fig. 11 is a fragmentary sectional view, taken on the plane of the line 11—11 of Fig. 7, looking in the direction of the arrows;

Fig. 12 is a fragmentary sectional view, taken on the plane of the line 12—12 of Fig. 7, looking in the direction of the arrows;

Fig. 13 is a fragmentary sectional view of the upper contact supporting arm, taken on a plane passing through the axis of the arm, showing a modification;

Fig. 14 is a fragmentary sectional view, taken on the plane of the line 14—14 of Fig. 13, looking in the direction of the arrows;

Fig. 15 is a fragmentary sectional view, taken on the plane of the line 15—15 of Fig. 13, looking in the direction of the arrows.

Referring to Fig. 1, 20 indicates a fused drop-out cut-out assembly, which may be supported from a cross arm 21 by means of a pair of clamping brackets 22 clamped on the arm by tight bolts 23.

The clamping brackets 22 support an insulator 24 by means of a central clamping band 25; and the insulator 24 is provided with reduced cylindrical portions at each of its ends for receiving the clamping bands 26, 27, which carry the contact arms that support the fuse tube unit 28.

The upper contact arm may consist of a pair of the spring contacts 29, shown in Fig. 1, these contacts consisting of resilient wire bent into substantially U shape, with two separate wires 30, 31, terminating at an easy bend 32.

One of the wires 29 preferably has a full helical loop 33 for increasing its resiliency. The wires 30, 31 are bent toward each other at 34 and 35, being provided with transverse crossing portions 36, 37. The transverse portions 36 and 37 support the curved parts 38 and 39, each of which partially embraces the cylindrical trunnion 40 of the fuse tube unit.

Beyond the curved portions 38, 39 the wires 20 close slightly upon the trunnion at the humps, indicated at 41; and thereafter the wires diverge at 42 and 43 to provide a bell mouthed opening for receiving the trunnions and guiding them into the position of Fig. 1.

The contact wire 31 has a yoke at 44, which joins two legs of similar shape. The contact wire 30 is bent upwardly at 45 and has a yoke at 46 joining two wires of similar shape. The curved ends 32 are made of this shape so that 30 they can be caught in the groove of a connector fixture 47, where they are clamped in grooves of similar shape.

The connector fixture 47 may consist of a substantially rectangular body 48, having an upward extension 49 that serves as a connector. The integral extension 49 has a through bore 50 and a partially spherical socket 51.

The upper surface of this extension 49 is formed with a pair of V grooves 52, one on each side of the hole 50, for receiving the tap wire 53 (Fig. 5).

Referring to Fig. 12, this is a view showing the tap wire 53 clamped by the connector bolt 54. The connector bolt 54 has an annular head 55 with a through bore 56 for receiving the tap wire. The annular head carries an extension 57 on each of its opposite sides, for engaging the tap wire 53 above the V grooves 52. The annular head 55 has a threaded shank 58, which passes through the hole 50; and on the opposite side of the connector extension 49 there is a spring washer 59 and a nut 60.

Referring again to Fig. 5 and Fig. 6, the body 48 may be hollow, having a rectangular hole 61 extending through it, this hole being bounded by the sides 62, 63 and by the top 64 and bottom 65. The sides 62, 63 have registering apertures 66 for one screw bolt 67, and the other registering apertures 68 for the other screw bolt 69.

The sides are formed with an outwardly projecting ledge 70 below the wire 30 and a similar outwardly projecting ledge 71 above the wire 29.

At the left side of the body 48 (Fig. 5 and Fig. 6) there is a curved groove 72, which fits the 66 curved end portions 32 of the two contact wires 29 and 30 when they are placed inside the flanges 70 and 71 outside of the bolts which pass through the holes 66 and 68.

The clamping band 26 may consist of two separate half cylindrical parts, indicated at 73, 74. On the left side these partly cylindrical bands have a short attaching flange 75, which is joined by a through clamping bolt 76. On the right side of Fig. 2 these partly cylindrical bands 73, 74

have a longer attaching flange 77, in each case with holes that register with the holes 66 and 68, for receiving the screw bolts 78, 79.

The attaching flanges 77 are thus adapted to engage on the outside of the connector fixture 48, to clamp the wires 29 and 30 in the grooves 72; and the wires are also confined above and below by the flanges 70 and 71 (Fig. 5).

The upper contact springs 29 and 30 are provided with initial tension toward each other so that they tend to close the tapered opening, which is formed by the portions 42, 43, but these portions are cammed apart by the upper trunnion 40 of the fuse unit 28, so that the curved portions grip the upper trunnion 40 and provide a connection with a low contact resistance.

The fuse tube unit 28 comprises a tubular insulating member 80, which is provided with an insulating liner 81, and the insulating tube 80 supports an upper contact fixture 82 and a lower contact fixture 83. The upper contact fixture 82 comprises a substantially cylindrical metal member which is threaded to receive the cap 84 that clamps the upper button which is carried by the fuse cable.

The cylindrical body of the upper contact 82 has a pair of integral laterally projecting cylindrical trunnions 40 (Figure 2) and these trunnions are preferably arranged toward the outer side of the contact fixture 82, that is toward the right, so that the jet action from the lower end of the tube 80 tends to rotate the fuse tube unit 28 in a clockwise direction about the upper trunnions 40. This tends to keep the lower fixture 83 in engagement with its contact arm until the jet action has ceased, and prevents mechanical disengagement at the lower end until the arc is extinguished.

The upper contact fixture 82 preferably has a downward extension 85 on its right side which carries an integral metal operating ring 86, by means of which the fuse tube unit is manipulated, using a fuse disconnect stick.

Both the fixtures 82 and 83 have cylindrical bores for receiving the tube 80, and the tube may be secured in these fixtures in each case by transversely extending riveted pins 87, which are arranged at such a point that they merely groove the outside of the tube 80 and are insulated and spaced from the fuse cable.

The lower contact fixture 83 has a cylindrical body provided with the bore 88 for tube 80, and bore 88 communicates with a downwardly open blast chute 89. This blast chute comprises a pair of parallel side walls 90 and a curved rear wall 91, which extends at its lower edge to the axis of the tube 80 and tends to direct the gases forwardly and downwardly toward the right, away from the operator.

The lower contact fixture 83 has a laterally projecting body 92 which is provided with a cylindrical bore 93 for housing a compression coil spring 94. In addition to housing the coil spring the extension 92 carries an integral manipulating ring 95 which may be engaged by a disconnect stick or the like.

The extension 92 also carries a pair of pivot flanges 96 which are parallel to each other and provided with a through bore for receiving the pintle 97 of a fuse ejector lever 98. The fuse ejector lever 98 comprises an elongated metal member which may have a flat body 99, generally surrounded by laterally projecting border flanges 100.

The flat body 99 carries a cylindrical hinge

formation 101 at its right side (Figure 7) for receiving the rivet 97, by means of which the ejector lever 98 is pivoted. The end wall of the fixture extension 92 is indicated at 102, and it is curved about the hinge formation 101 and has a flat stop surface 103 at its end for definitely limiting the pivotal movement of the ejector lever 98 by engaging the flat side 104.

The ejector lever 98 has a V-shaped notch 105 formed on the side toward the compression spring 94, and a bifurcated metal strut 106 has its legs extending on both sides of the body 99 of the ejector lever in this notch 105.

The border wall 100, previously mentioned, engages the lower side of the strut 106 and keeps it from sliding out of the notch 105 in Figure 7. The other end of the strut 106 has an end portion 107 of reduced width which passes through an aperture in a metal disc 108 and extends into the spring 94. Thus the spring is enabled to bear upon the strut 106 by means of the disc 108, and spring 94 urges the ejector lever 98 in a clockwise direction about its pivot 97.

The ejector lever 98 also carries a tubular portion 109, the details of which are shown in Figure 9, and this tubular portion has a through bore 110 for receiving a clamping button 111. The clamping button 111 has a tubular part 112 extending into the bore 110, and has a circular head 113 for clamping the cable leader 114.

The tubular part 112 has a threaded bore 115 for receiving the threaded portion 116 of a screw bolt having a wing head 117. The annular lower surface 118 of the wing head engages the end of the tubular portion 109. As the wing head 117 is turned clockwise it is threaded into the button 111, and draws the button head 113 inward, clamping the leader 114.

The ejector lever 98 also has a tapered extension 119, Figure 7, which terminates in a grooved end 120, the two legs 121 of which are located on the two sides of the fuse leader 114. Thus the fuse leader may be tensioned, as shown in Figure 1, by pivoting the ejector lever counterclockwise from the position of Figure 7 to that of Figure 1, compressing the spring 94; and thereafter passing the leader 114 downward through the groove 120 in the ejector lever 98, and backward toward the left about the clamping button 111 where the end of the lever is secured by turning the wing nut 117.

The ejector lever also carries a pair of integral laterally projecting trunnions 122, Figure 7, and these trunnions are adapted to provide a pivotal support for the fuse tube unit 28 on the lower contact fixture.

When the fuse tube unit is provided with a fuse as shown in Figure 1, the ejector lever 98 is held rigidly in fixed position with respect to the fuse tube unit 28. The trunnions 122 are located lowermost below the pivot 97 of the ejector lever, as shown in Figure 1.

The ejector lever has a tapered rearward extension 123, Figure 1, which is provided with a transverse pin 124. This pin engages the free end of a wire spring 125, which is used at a certain stage in the operation of the cut-out to eject the lower contact fixture 83 from engagement with its contact arm, which will now be described in detail.

The lower contact arm is carried by the clamping band 27. This clamping band may be constructed just like the upper clamping band 26, and its attaching flanges 126, 127, Figure 3, are apertured to receive the two screw bolts 128, 129.

These screw bolts 128, 129 support a lower contact arm fixture 130. The contact arm fixture 130 has its rear or left end hollow, having a rectangular through aperture 131 provided with a top wall 132, a bottom wall 133 and a pair of side walls 134, Figure 7. The side walls 134 are apertured to pass the screw bolts 128, 129, which pass through these side walls and through the clamping flanges 126, 127 to secure the contact arm fixture 130 to the clamping band 27.

The contact arm fixture 130 is formed with a hood for enclosing the mechanism, this hood being open at the bottom and the front side. The hood is formed by a rear wall 135, a pair of side walls 136 and a top wall 137. The same screw bolts 128 and 129, previously mentioned, are used to support the spring 125. Spring 125 has one end provided with a circular loop 138 extending about the screw bolt 128. It then has a diagonal portion 139 and a curved portion 140 which extends over the bolt 129 and terminates in a relatively straight free end portion 141.

The spring 125 may be U-shaped, having a transverse yoke 142 at its lowermost portion, in Figure 7, and there may be two legs which engage about the bolts 128, 129. Thus the yoke 142 may be located transversely of the border wall 100 of the ejector lever 98, so that the spring 125 engages the left side of the ejector lever and tends to force the entire fuse tube unit toward the right, away from the hooded fixture 130.

The fixture 130 also carries a connector similar to the one described in detail in Figure 5, this connector being carried by an integral flange 143 which carries a threaded bolt with an elongated head 144. The tap wire is indicated at 145.

The side walls 136 of the hood, of fixture 130, are closer together at the bottom, as seen in Figure 3, having an offset at 146. This offset portion is formed with an inwardly open groove 147 on the inside of each side wall for receiving the laterally projecting trunnions 122 on the ejector lever 98.

The inwardly open grooves 147 on the side walls 136 extend backwardly and upwardly in Figure 7, being defined on the right side by the partition 148. On the rear side the groove is defined by a curved surface 149 so that the groove 147 is rearwardly open to receive the trunnions 122.

At its lower end the groove 147 has a cylindrical portion 150, where the trunnions 122 come to rest. The curved wall 149 extends upward to a curved corner 151, and is joined to a substantially straight top wall 152, which extends forwardly and downwardly out of the open side 153 of the hood.

The opening between the wall 152 and the partition 148 tapers backwardly and becomes wider forwardly, and the wall portions indicated at 154 are more widely spaced than the wall portions 136. Wall portions 154 are spaced widely enough to clear the ends of the trunnions 122.

The operation of this part of the cut-out is as follows:

Assuming the fuse tube unit 28 has been provided with a fuse and the ejector lever has been tensioned, and the cable lead secured by being clamped under the button 111, the fuse tube unit 28 may be lifted by a disconnect stick, the end of which passes through the ring 95.

The fuse tube unit 28 will then hang downward from the ring 95, being upside down, as shown in dotted lines at the bottom of Figure 1. With the unit in this position the ring 95 is out of

the hood and the trunnions 122 are located uppermost, projecting laterally in both directions.

The contact fixture 95 may then be inserted into the contact arm fixture 130, or hood, and the trunnions 122 will pass below the wall 162 and above the partition 148 until the trunnions 122 reach the curved back wall 149. Then the fuse tube unit may be permitted to settle down and the trunnions 122 will pass into the groove 147 and come to rest upon the curved portion 150, which serves as a bearing.

The fuse tube unit is now in the position shown in dotted lines at the bottom of Figure 1. The operator may then remove the disconnect stick from the ring 95 and place it in the ring 86, and by manipulating the stick the operator may rotate the fuse tube unit 28 counterclockwise, in Figure 1, on its trunnions 122, in the lower bearing 150, until the upper trunnions 40 move into the tapered opening 43, 44 between the contact springs 29 and 30.

The counterclockwise motion is continued until the upper trunnions 40 spread the contact springs and move into the curved portions of these wires behind the hump 41. Then the upper contact wires will retain the upper trunnions 40, but it is possible to use the device as a manual disconnect by merely pulling on the ring 86 with a disconnect stick. Such a pull would move the fuse tube unit 28 clockwise to the position at the bottom left of Figure 1, indicating that it was purposefully opened as a disconnect.

The operation of the fused cut-out, upon occurrence of a fault in the circuit which melts the fuse, is as follows:

When the fuse melts, the tension on the leader 114, which is caused by the spring 94, and ejector lever 98, pulls the leader 114 out of the tube 80, and the ejector lever 98 is permitted to rotate from the position of Figure 1 to that of Figure 7.

During this rotation of the ejector lever, the trunnions 122 move in an orbit about the ejector lever 98, pivot 97, and the groove 147 is suitably curved to define this orbit. Thus the trunnions 122 move upward out of the groove 147 until when the ejector lever comes to a stop the trunnions 122 are out of the groove 147 and in the open portion of the hood which opens out at 153.

In the meantime the spring 125 has been engaging the ejector lever, tending to move it toward the right, but the spring 94 is stronger and the spring 94 causes the ejector lever to rotate counterclockwise to the position of Figure 7, when the stop surface 103 engaged by side 104 limits further movement of the ejector lever.

The spring 125 then comes into play and it urges the ejector lever and the whole contact fixture 83 toward the right, in Figure 7, ejecting the contact fixture 83 from the hood 130, aiding the force of gravity which tends to produce this same result.

The jet action which is caused by the blast of gases out of the lower end of the tube 80 tends to rotate the fuse tube unit 28 clockwise at its lower end about the upper trunnion 40. This jet action tends to keep the lower contact fixture 83 in the hood until the jet action has stopped.

The jet action is resisted by the ring 95 engaging the inside of the top wall 137, which is preferably provided with a downward curve at 155, tending to trap the ring 95 under the hood until the jet action has ceased. This definite stop, provided by the top wall 137 engaging ring 95, prevents the jet action from over-tensioning the upper

contact springs 29 and 30 so that these contact springs are not damaged.

Referring to Figures 13 to 15, these show a modified form of upper contact arms for engaging the same fuse tube unit. In this case the upper clamping band 26 has its attaching flanges 77 secured to a cast metal fixture 156 by a pair of through screw bolts 157, 158.

The fixture 156 has a rearwardly extending box-like portion 159, the side walls 160 of which are apertured to receive the bolts 157, 158. In order to permit a limited pivotal movement of the fixture 156 on its support the one aperture 161 fits the bolt 158, but the other aperture 162 is made oval in shape, being elongated in such direction as to permit pivotal movement about the bolt 158.

The fixture 156 has an integral upwardly extending flange 163, with a connector bolt 164, similar to those previously described for securing the tap wire 165. Fixture 156 extends forwardly toward the right from the box-like portion 159, and has a downwardly open cylindrical socket 166 for receiving a compression spring 167.

In general, the fixture 156 is open on its lower 25 side, being protected on its upper side by a top wall 168, which protects the mechanism, and by a pair of side walls 169 which protect and enclose both sides of the upper mechanism.

The side walls 169 are parallel to each other 30 and are provided with apertures for receiving rivets or pins 170, which provide a pivotal support for a lower rigid jaw member 171. The jaw member 171 comprises a metal casting of substantially U-shape, having a pair of legs 172, 173, which are angular in cross section and which are provided with an outwardly curved end portion 174 for guiding the fuse tube unit between the legs.

The yoke 175 may carry a triangular extension 176, with an upwardly extending integral pin 177 for engaging the spring 167. Thus the spring 167 urges the lower jaw 171 counterclockwise, tending to clamp the upper trunnions 40.

The legs 172, 173 may have a partially cylindrical depression at 178, Figure 13, where they are intended to engage the trunnions 40; and the top 45 of these legs 173, 174 may be provided with a downwardly curved end portion 179, to provide a tapered opening for guiding the trunnions 40 into the space between the hood 156 and the lower jaw 171.

The casting 156 is formed on its right end with a top wall 168 and with side walls 169, forming a hood. The top wall 168 and side walls 169 define a downwardly open box-like member which has an offset 180, Figure 15, on each side, the offset supporting downward wall extensions 181.

The offsets 180 are not straight from front to back or left to right, but are formed with a partially cylindrical portion 182, Figure 13, which is open downwardly and toward the right in Figure 13. Thus the partially cylindrical portion 181 of the hood is opposed by the partially cylindrical portion 178 of the lower jaw 171.

These two partially cylindrical portions close 60 about the trunnion 40, retaining it between the jaws but permitting rotation. Thus the fuse tube unit can rotate about the upper trunnions 40 when the fuse blows or it can be used as a disconnect by using the upper ring 183.

This upper contact fixture has the facility of adjusting itself to fuse tube units of different length, as may be encountered due to the ordinary in accuracies resulting from mass production. If the fuse tube unit is longer, its trunnions 40 will engage the lower side 184 of offsets 180 and tend

to pivot the casting 156 clockwise about the bolt 158, this being permitted by the elongated aperture 162.

If the fuse tube unit is shorter than usual the upper contact fixture 156 may pivot in the opposite direction.

It will thus be observed that we have invented an improved fused drop-out cut-out which has the following advantages:

1. It is adapted to use standard universal fuse links of any manufacturer and to be handled according to conventional practice.

2. The lower contact of the fuse tube is ejected from the bottom contact arm upon rupture of the fuse link so that the fuse tube will hang with its opening extending downward after operation, thus protecting the interior of the fuse tube from all adverse weather conditions.

3. The construction of the mechanism is such that the mechanical opening of the lower contacts is delayed until the arc has been definitely extinguished.

4. The jet action from the lower end of the tube tends to keep the upper end of the fuse tube in its proper position and to hold the lower end in position until after the blast, thus delaying mechanical opening until the arc has been extinguished.

5. The resilient spring contacts with their wide flaring ends are adapted to register with the trunnions of the fuse tube units, even though the dimensions may vary due to manufacturing tolerances and the contacts may give sufficiently to become self-aligning as they engage the trunnions.

6. Any undue strain on the spring contacts is prevented by the provision of stop surfaces which take the thrust that is caused by jet action during rupture of a fuse.

7. The present fuse unit may be operated as a disconnect switch, but when so operated its automatic mechanism is still "trip-free," so that a fault on the line will open the lower contacts even while the operator is closing and holding the upper contacts.

8. The device gives a visual indication at all times whether it is actively in the circuit or whether the circuit has been broken purposefully at the top or automatically by rupture of a fuse at the bottom.

9. The present device is adapted to effect a self-alignment of the contacts and to accommodate manufacturing tolerances in the length of the fuse unit independent of the portions which grip the contacts. Shocks which might be imparted to the fragile fuse link element upon the closing of the fuse tube unit with its contact arms are substantially reduced and practically eliminated, as the slamming of the fuse tube into position forces the ejector arm against the bottom of the fuse tube and does not tend to place additional tension on the fuse link element.

While we have illustrated a preferred embodiment of our invention, many modifications may be made without departing from the spirit of the invention, and we do not wish to be limited to the precise details of construction set forth, but desire to avail ourselves of all changes within the scope of the appended claims.

Having thus described our invention, what we claim as new and desire to secure by Letters Patent of the United States, is:

1. In a fused drop-out cut-out, the combination of an insulating support with upper and lower spaced contact arms carried by said support, a

fuse tube unit comprising an insulating tube open at the bottom and closed at the top, said tube having upper and lower contact fixtures and supporting and enclosing a tensioned fuse engaging said fixtures, both said fixtures being provided with a pair of oppositely directed aligned trunnions, and the upper contact arm being provided with open jaws for receiving and supporting the upper trunnions for rotation, the lower contact fixture comprising a laterally projecting part extending toward the lower contact arm and pivotally supporting an ejector lever, said ejector lever being attached at its end to the fuse and carrying the lower trunnions below the point of pivotal support of the ejector lever, spring means for urging said ejector lever about its pivot to tension the fuse and to move the ejector lever trunnions backwardly and upwardly in an orbit, said lower contact fixture being provided with a pair of spaced side walls for receiving the laterally projecting part of said lower contact fixture, and said walls being formed with inwardly extending guide surfaces engaging the top of the ejector lever trunnions to guide them backwardly and downwardly into backwardly and upwardly open bearing grooves carried by said walls, the pivotal movement of said ejector lever upon blowing the fuse moving the ejector trunnions backwardly and upwardly out of said grooves into an open space below said guide means to release the trunnions by gravity from the lower contact fixture.

2. In a fused drop-out cut-out, the combination of an insulating support with upper and lower spaced contact arms carried by said support, a fuse tube unit comprising an insulating tube open at the bottom and closed at the top, said tube having upper and lower contact fixtures and supporting and enclosing a tensioned fuse engaging said fixtures, both said fixtures being provided with a pair of oppositely directed aligned trunnions, and the upper contact arm being provided with open jaws for receiving and supporting the upper trunnions for rotation, the lower contact fixture comprising a laterally projecting part extending toward the lower contact arm and pivotally supporting an ejector lever, said ejector lever being attached at its end to the fuse and carrying the lower trunnions below the point of pivotal support of the ejector lever, spring means for urging said ejector lever about its pivot to tension the fuse and to move the ejector lever trunnions backwardly and upwardly in an orbit, said lower contact fixture being provided with a pair of spaced side walls for receiving the laterally projecting part of said lower contact fixture, and said walls being formed with inwardly extending guide surfaces engaging the top of the ejector lever trunnions to guide them backwardly and downwardly into backwardly and upwardly open bearing grooves carried by said walls, the pivotal movement of said ejector lever upon blowing the fuse moving the ejector trunnions backwardly and upwardly out of said grooves into an open space below said guide means to release the trunnions by gravity from the lower contact fixture, the said lower contact fixture being provided with second spring means engageable by the ejector lever spring means, the said second spring means serving after the ejector lever has moved to release its trunnions to assist the force of gravity in expelling the lower contact fixture from the lower contact arm.

3. In a fused drop-out cut-out, the combination of an insulating support with upper and lower spaced contact arms carried by said sup-

port a fuse tube unit comprising an insulating tube open at the bottom and closed at the top, said tube having upper and lower contact fixtures and supporting and enclosing a tensioned fuse engaging said fixtures, both said fixtures being provided with a pair of oppositely directed aligned trunnions, and the upper contact arm being provided with open jaws for receiving and supporting the upper trunnions for rotation, the lower contact fixture comprising a laterally projecting part extending toward the lower contact arm and pivotally supporting an ejector lever, said ejector lever being attached at its end to the fuse and carrying the lower trunnions below the point of pivotal support of the ejector lever, spring means for urging said ejector lever about its pivot to tension the fuse and to move the ejector lever trunnions backwardly and upwardly in an orbit, said lower contact fixture being provided with a pair of spaced side walls for receiving the laterally projecting part of said lower contact fixture, and said walls being formed with inwardly extending guide surfaces engaging the top of the ejector lever trunnions to guide them backwardly and downwardly into backwardly and upwardly open bearing grooves carried by said walls, the pivotal movement of said ejector lever upon blowing the fuse moving the ejector trunnions backwardly and upwardly out of said grooves into an open space below said guide means to release the trunnions by gravity from the lower contact fixture, the said walls being joined by an upper wall forming a hood, and the said hood engaging the top of said laterally projecting part of the lower contact fixture to resist the jet action of the fuse tube unit upon blowing of a fuse.

4. In a fused drop-out cut-out, the combination of an insulating support with upper and lower spaced contact arms carried by said support, a fuse tube unit comprising an insulating tube open at the bottom and closed at the top, said tube having upper and lower contact fixtures and supporting and enclosing a tensioned fuse engaging said fixtures, both said fixtures being provided with a pair of oppositely directed aligned trunnions, and the upper contact arm being provided with open jaws for receiving and supporting the upper trunnions for rotation, the lower contact fixture comprising a laterally projecting part extending toward the lower contact arm and pivotally supporting an ejector lever, said ejector lever being attached at its end to the fuse and carrying the lower trunnions below the point of pivotal support of the ejector lever, spring means for urging said ejector lever about its pivot to tension the fuse and to move the ejector lever trunnions backwardly and upwardly in an orbit, said lower contact fixture being provided with a pair of spaced side walls for receiving the laterally projecting part of said lower contact fixture, and said walls being formed with inwardly extending guide surfaces engaging the top of the ejector lever trunnions to guide them backwardly and downwardly into backwardly and upwardly open bearing grooves carried by said walls, the pivotal movement of said ejector lever upon blowing the fuse moving the ejector trunnions backwardly and upwardly out of said grooves into an open space below said guide means to release the trunnions by gravity from the lower contact fixture, the said walls being joined by an upper wall forming a hood, and the said hood engaging the top of said laterally projecting part of the lower contact fixture to resist the jet action of the fuse tube unit

5 upon blowing of a fuse, and said hood being downwardly curved at its forward end, tending to retain the lower contact fixture until the jet action of the fuse tube unit ceases and the circuit is broken, so that the lower contact fixture will not be released until the circuit is broken in the fuse tube.

5. In a fused drop-out cut-out, the combination of an insulating support with upper and lower spaced contact arms carried by said support, a fuse tube unit comprising an insulating tube open at the bottom and closed at the top, said tube having upper and lower contact fixtures and supporting and enclosing a tensioned fuse engaging said fixtures, both said fixtures being provided with a pair of oppositely directed aligned trunnions, and the upper contact arm being provided with open jaws for receiving and supporting the upper trunnions for rotation, the lower contact fixture comprising a laterally projecting part extending toward the lower contact arm and pivotally supporting an ejector lever, said ejector lever being attached at its end to the fuse and carrying the lower trunnions below the point of pivotal support of the ejector lever, spring means for urging said ejector lever about its pivot to tension the fuse and to move the ejector lever trunnions backwardly and upwardly in an orbit, said lower contact fixture being provided with a pair of spaced side walls for receiving the laterally projecting part of said lower contact fixture, and said walls being formed with inwardly extending guide surfaces engaging the top of the ejector lever trunnions to guide them backwardly and downwardly into backwardly and upwardly open bearing grooves carried by said walls, the pivotal movement of said ejector lever upon blowing the fuse moving the ejector trunnions backwardly and upwardly out of said grooves into an open space below said guide means to release the trunnions by gravity from the lower contact fixture, said upper jaws comprising a pair of U-shaped wires, one on each side of the fuse tube unit, the U-shaped wires crossing each other behind the upper trunnions, where they are formed with said jaws.

6. In a fused drop-out cut-out, the combination of an insulating support with upper and lower spaced contact arms carried by said support, a fuse tube unit comprising an insulating tube open at the bottom and closed at the top, said tube having upper and lower contact fixtures and supporting and enclosing a tensioned fuse engaging said fixtures, both said fixtures being provided with a pair of oppositely directed aligned trunnions, and the upper contact arm being provided with open jaws for receiving and supporting the upper trunnions for rotation, the lower contact fixture comprising a laterally projecting part extending toward the lower contact arm and pivotally supporting an ejector lever, said ejector lever being attached at its end to the fuse and carrying the lower trunnions below the point of pivotal support of the ejector lever, spring means for urging said ejector lever about its pivot to tension the fuse and to move the ejector lever trunnions backwardly and upwardly in an orbit, said lower contact fixture being provided with a pair of spaced side walls for receiving the laterally projecting part of said lower contact fixture, and said walls being formed with inwardly extending guide surfaces engaging the top of the ejector lever trunnions to guide them backwardly and downwardly into backwardly and upwardly open bearing grooves carried by

said walls, the pivotal movement of said ejector lever upon blowing the fuse moving the ejector trunnions backwardly and upwardly out of said grooves into an open space below said guide means to release the trunnions by gravity from the lower contact fixture, the said trunnions on the upper contact fixture being located on that side of the tube unit which is away from the insulating support, the jet action from the fuse tube tending to rotate the fuse tube clockwise about the upper trunnions and tending to retain the lower contact fixture in engagement with the lower contact arm.

7. In a fused drop-out cut-out, an upper contact structure comprising an insulating support, metal band means extending about the insulating support and having a pair of parallel flanges, a connector block located between said parallel flanges and having a pair of through bores registering with bores in the flanges, said connector block having each of its opposite faces formed with a forwardly open U-shaped groove facing each flange, a pair of substantially U-shaped wire contact members, each contact member having curved portions clamped between said flanges and spacer block, and said U-shaped wire contacts having forwardly extending portions formed adjacent their ends with partially circular trunnion bearings.

8. In a fused drop-out cut-out, an upper contact structure comprising an insulating support, metal band means extending about the insulating support and having a pair of parallel flanges, a connector block located between said parallel flanges and having a pair of through bores registering with bores in the flanges, said connector block having each of its opposite faces formed with a forwardly open U-shaped groove facing each flange, a pair of substantially U-shaped wire contact members, each contact member having curved portions clamped between said flanges and spacer block, and said U-shaped wire contacts having forwardly extending portions formed adjacent their ends with partially circular trunnion bearings, said contact wires crossing each other upwardly and downwardly backward of said trunnion bearing portions.

9. In a fused drop-out cut-out, a lower contact structure comprising an insulating support, a clamping band carried by said insulating support, a contact fixture secured to said clamping band by through bolts, said contact fixture having a downwardly extending rear wall, forwardly extending parallel side walls, and a forwardly extending top wall, the said side walls being provided with inwardly facing recesses, each recess being open at the front edge of said side walls and extending backwardly toward the back wall and curving downwardly and forwardly under a rearwardly extending partition carried by each wall.

10. In a fused drop-out cut-out, a lower contact structure comprising an insulating support, a clamping band carried by said insulating support, a contact fixture secured to said clamping band by through bolts, said contact fixture having a downwardly extending rear wall, forwardly extending parallel side walls, and a forwardly extending top wall, the said side walls being pro-

vided with inwardly facing recesses, each recess being open at the front edge of said side walls and extending backwardly toward the back wall and curving downwardly and forwardly under a rearwardly extending partition carried by each wall, the said through bolts carrying a fuse tube, and an ejecting spring comprising a U-shaped spring member passing over one through bolt and under and about the other screw bolt.

11. In a fused drop-out cut-out, a lower contact structure comprising an insulating support, a clamping band carried by said insulating support, a contact fixture secured to said clamping band by through bolts, said contact fixture having a downwardly extending rear wall, forwardly extending parallel side walls, and a forwardly extending top wall, the said side walls being provided with inwardly facing recesses, each recess being open at the front edge of said side walls and extending backwardly toward the back wall and curving downwardly and forwardly under a rearwardly extending partition carried by each wall, and a fuse tube unit provided with a lower contact fixture having a rearwardly extending part, said rearwardly extending part carrying a pair of aligned oppositely directed trunnions receivable between said side walls, the said trunnions passing backwardly and about the end of said partition into a lower part of said recesses.

12. In a fused drop-out cut-out, a lower contact structure comprising an insulating support, a clamping band carried by said insulating support, a contact fixture secured to said clamping band by through bolts, said contact fixture having a downwardly extending rear wall, forwardly extending parallel side walls, and a forwardly extending top wall, the said side walls being provided with inwardly facing recesses, each recess being open at the front edge of said side walls and extending backwardly toward the back wall and curving downwardly and forwardly under a rearwardly extending partition carried by each wall, and a fuse tube unit provided with a lower contact fixture having a rearwardly extending part, said rearwardly extending part carrying a pair of aligned oppositely directed trunnions receivable between said side walls, the said trunnions passing backwardly and about the end of said partition into a lower part of said recesses, the said trunnions being carried by a pivoted ejector lever, spring pressed to move in such a direction as to withdraw the fuse and move the trunnions backwardly, upwardly, and forwardly out of said recesses.
